United States Patent Office.

DAVID MANUEL, OF BOSTON, MASSACHUSETTS, ASSIGNOR TO HIMSELF
AND WILLARD MANUEL, OF SAME PLACE.

Letters Patent No. 72,212, dated December 17, 1867.

STOVE-PIPE DAMPER.

The Schedule referred to in these Letters Patent and making part of the same.

TO ALL WHOM IT MAY CONCERN:

Be it known that I, DAVID MANUEL, of Boston, in the county of Suffolk, and State of Massachusetts, have invented a new and useful Improvement in Stove-Pipe Dampers; and I do hereby declare that the following is a full, clear, and exact description thereof, which will enable others skilled in the art to make and use the same, reference being had to the accompanying drawings, forming part of this specification, in which—

Figure 1 is a top or bottom view of my improved damper, both sides being alike.

Figure 2 is an edge view of the damper when the pivot-rod is out.

Figure 3 is a section taken in the line $x x$, fig. 1.

Similar letters of reference indicate like parts.

This invention relates to an improvement in the construction of dampers for stove-pipes, and consists in two cast-iron disks which have flat central surfaces, and are interlocked, so that they lie close together when united by the pivot suspension-rod of the damper. They have fluted or corrugated edges, which overlap the opposite corrugations on the opposite disks, and form concave radiators above and below, so related to each other that the smoke and heated gases can enter therein from below and receive a reverse movement, which deflects them against the stove-pipe, thus imparting more heat to the air in a room before finally escaping.

Two cast-iron plates or disks, A A, made precisely alike, have a central part, B, made flat, so that the two disks may lie close together, and each part is countersunk or furrowed across the inner face, for receiving one-half of the pivot-rod a , which is held in place for locking the two disks A A together, by two bridge-loops, $b b$, on each of the disks, projecting through corresponding holes in the centre of each one, as shown in fig. 3. On the edge of each of the disks A A are curved wings, $c c$, which radiate from the centre, and rise crowning on the outside of the disks, as shown in figs. 1 and 2. The radiating wings are separated by spaces, $m m$, and are so placed in each disk that when the disks are put together they break joints with each other, and the spaces between them open into the concave sides of the radiators, as shown in fig. 2.

The damper is hung in a stove-pipe by the pivot-rod a , in the usual way, and it will be manifest that when the damper is closed as much as it can be, by turning it square with the pipe, the products of combustion will pass up through the spaces $m m$ between the radiating wings $c c$ of the lower disk, and strike the concave inside of the radiating wings $c c$ of the upper plate, from which they will be deflected against the walls of the stove-pipe, and impart a portion of their heat to it, before escaping through the spaces $m m$ between the wings $c c$ of the upper disk of the damper, thereby retaining the products of combustion as long as possible, without actually cutting off the draught.

Having thus described my invention, I claim as new, and desire to secure by Letters Patent—

A stove-pipe damper formed of two flat cast-iron disks, A A, united solidly in the middle, and interlocked by loops $b b$, upon the suspension-rod a , with concave radiating edges, $c c$, arranged and operating as herein described.

DAVID MANUEL.
